UNITED STATES PATENT OFFICE.

MORTON G. BUNNELL, OF CHICAGO, ILLINOIS, ASSIGNOR TO THE CORNING MANUFACTURING COMPANY, OF CHICAGO, ILLINOIS, A CORPORATION OF ILLINOIS.

EXHAUST-WHISTLE.

1,210,898.

Specification of Letters Patent.

Patented Jan. 2, 1917.

Application filed September 2, 1913. Serial No. 787,607.

To all whom it may concern:

Be it known that I, MORTON G. BUNNELL, a citizen of the United States of America, and resident of Chicago, Cook county, Illinois, have invented a certain new and useful Improvement in Exhaust-Whistles, of which the following is a specification.

My invention relates to chime whistles which are blown by the exhaust from motor boats or automobile engines.

Generally stated, the object of my invention is to provide a novel and highly efficient exhaust whistle of this kind.

A special object is to provide an exhaust whistle in which the opening of the exhaust valve not only throws the exhaust into the atmosphere, but also serves to render the whistle inoperative, and to prevent dust and dirt from entering the whistle while not in use, through the medium of a rod which slides endwise within the whistle, and which forms a medium of connection between the exhaust valve and some element of the sound producing means.

It is also an object to provide, in an exhaust whistle of this particular character, an automatic valve for closing communication between the exhaust and the sound producing means, when the exhaust valve is opened, and which will open automatically when the said exhaust valve is closed.

It is also an object to provide certain details and features of improvement tending to increase the general efficiency and desirability of an exhaust whistle of this particular character.

To the foregoing and other useful ends my invention consists in matters hereinafter set forth and claimed.

In the accompanying drawings, Figure 1 is a longitudinal section of an exhaust whistle embodying the principles of my invention, showing the same in condition to prevent blowing of the whistle, and to discharge the exhaust into the atmosphere.

Fig. 2 is a detail longitudinal section on line 2—2 in Fig. 1. Fig. 3 is a cross section on line 3—3 in Fig. 1. Fig. 4 is a cross section on line 4—4 in Fig. 1. Fig. 5 is a view similar to Fig. 1 showing another form of my invention. Fig. 6 is a detail longitudinal section on line 6—6 in Fig. 5. Fig. 7 is a cross section on line 7—7 in Fig. 5.

As thus shown, my invention comprises a stationary member A having an exhaust

inlet a connected with the exhaust of the engine. Said member also has an outlet a¹ for the exhaust, controlled by an outwardly opening valve B, which latter is held normally open by a spring b, whereby the whistle is normally inoperative. Discharge openings a² are provided in the side of the body opposite the said outlet a¹, of any suitable number, and connection between these openings and the exhaust is controlled by a valve C, which is normally closed, and which is fixed on the longitudinally disposed rod c of the whistle. This rod had its end arranged to engage a roller b¹ on the exhaust valve, whereby said rod is moved endwise to open said valve C when the valve B is opened.

The tubes D are disposed parallel around the rod c and are united by a sleeve d that slides over the tube d¹, which latter is fixed in the member A, forming a guide for said rod. A set screw d² is inserted through the sleeve d to engage the tube d¹, whereby the tubes D can be adjusted toward and away from the member A, in order to bring their ends in proper position relative to the slots a², whereby the proper tone is produced. The shell or sleeve E incloses the said tubes D, and slides thereon to close the openings between the member A and the ends of the tubes D, thus preventing the entrance of dust and dirt. This element E is secured to the rod c, whereby the whistle is rendered operative when the valve B is closed. A spring F connects the outer closed end of the shell E with the tube d¹, thus serving to pull the shell toward the member A, to close the openings a², when the valve B is opened after blowing the whistle. For this purpose, it will be understood, the said spring is fastened at its end in any suitable manner.

In Figs. 5 to 7 the construction is substantially the same as previously shown and described. In this case, however, the exhaust valve G is fixed on the end of the rod g, and the spring g¹ is interposed between the valve g² and the wall of the member H, as shown. Also, the sleeve or shell I is open at both ends, and has its outer end secured by a spider i to the said rod, which latter has an eye J for connection with the operating means. The tubes K are like those previously described, and the exhaust escapes from the slots h against the end edges of

said tubes, when the valve G is closed and the valve g^2 opened; and at such time the spring g^1 is compressed and the shell I is away from the member H , whereby the 5 whistle is in condition to operate.

As shown, the tubes D and the shell E are square in cross section, but it will be understood that this is not essential, and that tubes of any shape in cross section can 10 be used if necessary or desirable. As shown, a key d^3 is interposed between the sleeve d and tube d^1 to prevent rotation of the structure about the rod. Any other suitable means, however, can be employed for this 15 purpose, and with a view to maintaining the ends of the tubes D in proper relation to the slots a^2 , without interfering with the adjustment of the tubes D toward and from said slots. It is also obvious that the sleeve 20 or shell I shown in Figs. 5 and 7, can be connected with the rod g in any suitable or desired manner. This can be changed or modified as circumstances may require, without departing from the spirit of my invention. Again it is obvious that the arrangement of the spring g^1 can be changed or varied if necessary or desired, without interfering with the characteristic mode of 25 operation of my invention. For example, the parts can be so proportioned and formed that the said spring may be of greater length than shown.

I do not limit myself to the exact construction shown and described.

35 What I claim as my invention is:

1. An exhaust whistle-structure comprising a stationary member adapted to be connected with the exhaust, having an exhaust outlet and a fluid discharge opening, an element 40 having endwise motion toward and away from said opening, serving to control communication between the atmosphere and

the interior of the structure, said element being mounted on said member, an outwardly opening valve for said outlet, a connection between said element and valve, including a rod mounted to slide enwise in said member, and means to control the valve and rod, a device inside of said element for receiving the exhaust from said opening, thereby to produce the sound, means for adjusting said device toward and away from said opening. 45

2. An exhaust whistle comprising a hollow member having exhaust inlet and outlet openings, a passage through which the exhaust escapes to operate the whistle, an outwardly opening external valve for said outlet, and means serving to prevent the exhaust from escaping through said passage 50 when the said outlet is open, but not when the valve is closed, said outlet being disposed between said inlet and said valve, together with a spring for normally holding said valve in open position. 55

3. An exhaust whistle comprising a hollow member having exhaust inlet and outlet openings, a passage through which the exhaust escapes to operate the whistle, an outwardly opening external valve for said outlet, and means serving to prevent the exhaust from escaping through said passage 60 when the said outlet is open, but not when the valve is closed, said outlet being disposed between said inlet and said valve, said 65 means comprising a wall within said member. 70

Signed by me at Chicago, Illinois, this 29th day of August, 1913.

MORTON G. BUNNELL.

Copies of this patent may be obtained for five cents each, by addressing the "Commissioner of Patents, Washington, D. C."

It is hereby certified that the assignee in Letters Patent No. 1,210,898, granted January 2, 1917, upon the application of Morton G. Bunnell, of Chicago, Illinois, for an improvement in "Exhaust-Whistles," was erroneously described and specified as "The Corning Manufacturing Company," whereas said assignee should have been described and specified as *The Coming Manufacturing Company*, as shown by the records of assignments in this office; and that the said Letters Patent should be read with this correction therein that the same may conform to the record of the case in the Patent Office.

ed and sealed this 6th day of February, A. D., 1917.

[SEAL.]

R. F. WHITEHEAD,

Acting Commissioner of Patents.
